UNITED STATES PATENT OFFICE.

LEE A. COLLINS, OF LOUISVILLE, KENTUCKY.

AUTOMATIC TELEPHONE FIRE-ALARM.

1,252,665.

Specification of Letters Patent. Patented Jan. 8, 1918.

Application filed December 14, 1916. Serial No. 137,011.

To all whom it may concern:

Be it known that I, LEE A. COLLINS, a citizen of the United States, residing at Louisville, in the county of Jefferson and

5 State of Kentucky, have invented certain new and useful Improvements in Automatic Telephone Fire-Alarms, of which the following is a specification.

My invention relates to new and useful 10 improvements in fire alarms and more particularly to that type in which an audible signal is transmitted from a telephone line to the central station when the central may subsequently call up the fire department and 15 thereby give a certain alarm.

One of the primary objects of my invention consists in providing an alarm mechanism of the above described character which shall be automatically operated in case of 20 fire and which will act to raise the receiver hook of a telephone instrument to connect the instrument in line with the central station and which will give an audible signal which may be transmitted from the telephone line to the central station.

25 In this connection, one of the objects of my invention consists in providing an actuating device including a normally engaged latch lever and keeper which, when disengaged, release a weight having operative connection with the receiver hook so that the hook will be raised and the instrument connected in its circuit.

A still further object of my invention 30 consists in providing a normally open signal circuit adapted to be closed upon movement of the latch lever to release the keeper.

Another object which I have in view is 35 the provision of novel means for causing the release of the latch lever which includes a spring normally tending to swing it to released position and a stretched cord normally tending to hold it in active position, the cord being either extended about various parts of the structure to be protected 40 so that it will be burned in case of fire or being adapted to be mechanically severed through closing of a circuit controlled by thermostatic circuit closers.

45 In this connection, a still further object of my invention consists in the provision of a novel form of electrical device for severing the cord upon closing of a circuit by a thermostatic circuit closer.

50 With these and other objects in view, my invention will be fully described, illustrated

in the accompanying drawings and then specifically pointed out in the claims which are attached to and form a part of this application.

60 In the drawings:

Figure 1 is an elevational view illustrating my alarm system in use,

Fig. 2 is a front elevation of the actuating mechanism proper with its casing removed,

Fig. 3 is a section on the line 3—3 of Fig. 2, the casing being shown in dotted lines,

Fig. 4 is a perspective view of the actuating mechanism,

Fig. 5 is a view corresponding to Fig. 1 illustrating the employment of my system in connection with thermostatically operated circuit closers and mechanical means for severing the controlling cord,

70 Fig. 6 is a perspective view of one of the thermostatic circuit closers,

Fig. 7 is a corresponding view of the electrically operated cord severing mechanism.

As my fire alarm system is intended to 80 operate in connection with a telephone system in such a manner as to transmit an audible signal to the central station of the telephone company in case of fire, I have illustrated it in connection with a conventional 85 form of telephone instrument 10 having a receiver hook 11, the instrument being preferably mounted on any suitable support 12. Coöperating with this telephone instrument is an actuating mechanism indicated as a 90 whole by the numeral 13 and an audible signal device 14.

95 Referring to Figs. 2 to 4 inclusive for an understanding of the actuating mechanism 13, it will be seen that such mechanism includes a support 15 forming the back wall of a housing 16 which is open at its lower end. Vertically disposed spaced guides 17 are secured to the back wall 15 projecting at their lower ends to the bottom thereof 100 and a keeper 18 is pivoted at one end to the lower end of one of these guides and adapted, at its opposite end, to seat in a socket or recess 19 formed in the lower end of a latch lever 20 which is pivoted at its upper end 105 at 21 adjacent the upper portion of the housing and which normally hangs in a vertical position. A weight 22 is supported by the keeper 18 being free for sliding movement between the guides 17 and adapted to drop through the open bottom of the casing upon release of the keeper through 110

swinging of the latch lever 20. This weight, is provided, at its upper end, with an eye 23 and a cord 24 is connected at one end to the eye, is passed upwardly through a guide 5 ring 25 carried by the back wall 15 of the casing, forwardly through an opening 26 formed in the front wall of the casing and its free end is connected to the receiver hook 11. Obviously, if the weight 22 is released 10 by release of the keeper 18, it will act through the cord 24 to raise the receiver hook and connect the telephone instrument with the central station.

A cord 27 is secured, at one end, to an eye 15 28 carried by the latch lever in spaced relation to its pivoted end, is passed about an idler pulley or guide 29 mounted in the casing, through an opening in the top of the casing and is strung about various 20 parts of the house or other structure to be protected, being passed through guide rings 30 and fastened, at one end, as shown at 31. A weight 32 is loosely suspended upon any portion of this cord to hold it taut in 25 case of stretching and as will be apparent, this cord, as long as it remains under strain, will hold the latch lever in active engagement with the keeper 18. A helical spring 33 connected, at one end, to the latch lever 30 adjacent its free end is connected, at its opposite end, to a stud or pin 34 projecting from the back wall 15 of the casing and exerts a constant strain tending to swing the latch lever to inactive position to release 35 the keeper. Obviously, therefore, as soon as the cord 27 becomes severed, as by being burned, the latch lever will be swung to inactive position.

A stop bracket 35 is secured to the rear 40 wall of the casing in the path of the latch lever 20 to limit its movement under the action of the spring 33 and this bracket carries a contact 36 engageable by a contact 37 carried by the latch lever. A wire 38 leads 45 from a binding post 39 carried by the latch lever through an opening formed in the casing 16 to one terminal or pole of a battery 40 or other suitable source of electrical energy and a wire 41 leads from the stop 50 bracket 35 to one binding post of the audible signal device 14 which, in the present instance, is illustrated as an electrically operated gong. A wire 42 connects the other binding post of this gong with the other 55 pole of the battery.

In operation, in case of fire, the cord 27 or a portion of it will be destroyed by the fire with the result that the spring 33 will draw the latch lever 20 into engagement 60 with the bracket 35 to release the keeper 18. This movement of the latch lever will release the weight 22 causing the raising of the receiver hook of the telephone instrument and will also close a circuit from the 65 battery through the wire 38, latch lever 20,

contacts 37 and 36, bracket 35, wire 41, signal device 14 and wire 42 back to the battery. As a result, the audible signal device 14 will be continuously energized and its signal will be transmitted over the telephone line to the central station. The operator at the central station hearing this signal and, of course, knowing what instrument is transmitting it, may call up the fire department and give the notice of fire and its location. 70 75

Under some circumstances, an electrically controlled alarm system will be more desirable and such a system is illustrated in Figs. 5 to 7 inclusive. In these figures, the telephone instrument, actuating mechanism 13 and audible signal are identical and are indicated by corresponding reference numerals. The cord 27, however, instead of being run about various parts of the structure to be protected is run but a short distance from the casing and its end is secured to an eye screwed into the wall of the structure or any suitable support as indicated at 43. Co-operating with the above described portion 80 85 of the alarm system is an electrically actuated cord severing device indicated as a whole by the numeral 44 and a plurality of thermostatically operated circuit closers 45 connected in circuit with a source of energy 90 such as a battery 46 and with the cord severing device 44. Referring now more particularly to Fig. 7 of the drawings, the cord severing device includes a supporting base 47 carrying an electro-magnet 48 and adjacent each coil of the magnet, the standards 49 and 50. An armature 51 is hinged to the upper end of the standard 49 and is normally held away from the poles of the magnet by a leaf spring 52 carried by the standard. An L-shaped stop 53 supported by the standard 50 has its free arm extending in spaced relation to the standard to limit the swinging of the armature 51 away from the poles of the magnet through the action of the spring 52. The upper end of the standard 50 is provided with a slot 54 in alignment with the armature 51 and the armature, at its free end, is provided with a cutting blade 55, the edge of which is normally spaced somewhat above the standard 50. Upon energization of the magnet, this cutting blade is adapted to be drawn into the slot 54 to sever a cord extending across the slot. Obviously, the slot may be so proportioned relative to the taper of the cutting blade as to protect the edge portion proper of the blade and prevent its blunting in operation. This cord severing device is supported in any suitable manner so that a portion of the cord 27 will extend across the slot 54 in position to be severed when the magnet 48 is energized. A wire 56 leads from one terminal of the magnet coil to one 100 105 110 115 120 pole of the battery 46 and the wire 57 leads

from the other terminal of the magnet 48 to one of the contacts of the thermostatic circuit closer 45, a wire 58 leading from the other contact and this circuit closer to the 5 free pole of the battery 46. Obviously, any number of circuit closers 45 may be connected in the circuit by means of branch leads 59 and 60. Any suitable type of thermostatically operated circuit closer may 10 be employed, one form being illustrated in Fig. 6 in which two plates 61 and 62 of dissimilar metal are connected at one end as shown at 63, their connected ends being insulated from each other by a block or strip 15 of fiber 64 or other insulating material. The free ends of these strips carry upon their adjacent faces, contacts 65 adapted to be brought into engagement with each other when the temperature of the plates has 20 been sufficiently raised as would happen in case of fire. Of course, the fastening device 63 is insulated from the plates so that there is normally no electrical connection between them and the circuit forming wires 57 and 25 58 are connected one to each of the plates.

Although, I have illustrated and described my invention in all its details of construction, it will, of course, be apparent that numerous changes, both in details and in arrangement of parts may be made without departing from the spirit of my invention and I, therefore, reserve the right to make any changes which may be deemed advisable and which will fall within the scope of the 30 appended claims.

Having thus described the invention, what is claimed as new is:

1. In an alarm system, the combination with a telephone instrument including a receiver hook, of means releasable to raise the hook, means operable by the release of the first mentioned means for sounding an audible signal, and means operable under conditions necessitating an alarm signal for releasing the first mentioned means, said latter means including a cord under tension and adapted when disrupted to cause release of the first mentioned means, and electrically operated thermostatically controlled means 50 for disrupting the cord.

2. In an alarm system, the combination with a telephone instrument including a receiver hook, of a weight, connection between the weight and instrument whereby falling 55 of the weight will cause raising of the receiver hook, means normally supporting the weight but tending constantly to move out of supporting relation thereto, and a disruptive member normally holding the supporting means in active position.

3. In an alarm system, the combination with a telephone instrument including a receiver hook, of a weight, connection between the weight and instrument whereby falling 60 of the weight will cause raising of the re-

ceiver hook, means normally supporting the weight but tending constantly to move out of supporting relation thereto, and a disruptive member normally holding the supporting means in active position, said member comprising 70 a cord connected at one end to a fixed object and at its other end to the supporting means.

4. In an alarm system, the combination with a telephone instrument including a receiver hook, of a weight, connection between the weight and instrument whereby falling of the weight will cause raising of the receiver hook, means normally supporting the weight but tending constantly to move out 75 of supporting relation thereto, a disruptive member normally holding the supporting means in active position, said member comprising a cord connected at one end to a fixed object and at its other end to the supporting 80 means, and thermostatic means for disrupting the cord.

5. In an alarm system, the combination with a telephone instrument including a receiver hook, of a weight, connection between 90 the weight and instrument whereby falling of the weight will cause raising of the receiver hook, a swingingly mounted latch lever, a swingingly mounted keeper normally supported by engagement with the 95 latch lever and in turn supporting the weight, means constantly tending to swing the latch lever out of engagement with the keeper, disruptive means normally holding the latch lever in engagement with the 100 keeper, and means operable upon swinging of the latch lever out of engagement with the keeper for sounding a signal device.

6. In an alarm system, the combination with a telephone instrument including a receiver hook, of a weight, connection between 105 the weight and instrument whereby falling of the weight will cause raising of the receiver hook, a swingingly mounted latch lever, a swingingly mounted keeper 110 normally supported by engagement with the latch lever and in turn supporting the weight, means constantly tending to swing the latch lever out of engagement with the keeper, disruptive means normally holding the latch lever in engagement with the 115 keeper, and means operable upon swinging of the latch lever out of engagement with the keeper for sounding a signal device, said means including a contact disposed in 120 juxtaposition to the latch lever, and an electrical signal in a normally open circuit with the latch lever and contact, the latch lever when swung out of engagement with the keeper being adapted to engage the contact to close the circuit.

7. In an alarm system, the combination with a telephone instrument having a receiver hook, of a weight, connection between 125 the weight and instrument whereby 130

falling of the weight will cause raising of the receiver hook, supporting means for the weight, means constantly tending to cause the supporting means to move out of operative relation to the weight, a cord under tension holding said latter means from operation, and means operable upon disruption of the cord for sounding a signal.

8. In a fire alarm, the combination with 10 a telephone instrument having a receiver hook, of a weight, operative connection between the weight and instrument whereby falling of the weight will cause raising of the hook, a swinging latch lever, a keeper 15 normally engaging the latch lever, supporting the weight and adapted to release it when disengaged from the latch lever, means operable upon disengagement of the latch lever from the keeper for sounding 20 an alarm, means constantly tending to move the latch lever out of engagement with the keeper, and a tensioned cord normally holding the latch lever in engagement with the keeper.
- 25 9. In a fire alarm, the combination with a telephone instrument having a receiver hook, of a weight, operative connection between the weight and instrument whereby falling of the weight will cause raising of the hook, a swinging latch lever, a keeper 30 normally engaging the latch lever, supporting the weight and adapted to release it when disengaged from the latch lever, means operable upon disengagement of the 35 latch lever from the keeper for sounding an

alarm, means constantly tending to move the latch lever out of engagement with the keeper, a tensioned cord normally holding the latch lever in engagement with the keeper, and electrically operated thermostatically controlled means for disrupting the cord. 40

10. In a fire alarm, the combination with a telephone instrument having a receiver hook, of a weight, operative connection between the weight and instrument whereby falling of the weight will cause raising of the hook, a swinging latch lever, a keeper normally engaging the latch lever, supporting the weight and adapted to release it 45 when disengaged from the latch lever, means operable upon disengagement of the latch lever from the keeper for sounding an alarm, means constantly tending to move the latch lever out of engagement with the keeper, a tensioned cord normally holding the latch lever in engagement with the keeper, and electrically operated thermostatically controlled means for disrupting the cord. 50

55

60 In testimony whereof I affix my signature.

LEE A. COLLINS. [L. s.]
